US00D509993S

(12) **United States Design Patent** (10) Patent No.: **US D509,993 S**
 Lambert et al. (45) Date of Patent: **** Sep. 27, 2005**

(54) **WINE GLASS**

(75) Inventors: **Michael L. Lambert**, Eugene, OR (US); **K. Robin Baggett**, San Luis Obispo, CA (US); **Robert K. Schiebelhut**, San Luis Obispo, CA (US); **James I. Efird**, Arroyo Grande, CA (US); **William Turrentine**, Fairfax, CA (US); **Lori Evans Bartman**, Sylvania, OH (US)

(73) Assignee: **Snapdragon**, San Luis Obispo, CA (US)

(**) Term: **14 Years**

(21) Appl. No.: **29/183,035**

(22) Filed: **Jun. 4, 2003**

(51) LOC (8) Cl. **07-01**

(52) U.S. Cl. **D7/524; D7/537**

(58) Field of Search D7/509, 510, 511, D7/522, 524, 537, 528, 507, 523; D39/1; 220/629, 636, 630; 215/372, 377, 379, 235, 378; 65/112
